DESIGN FOR ELECTRICALLY LIGHTED SHOE

Augustin Mlcoch, Hulin, Czechoslovakia

Application November 4, 1937, Serial No. 72,621
In Czechoslovakia March 30, 1937

Term of patent 7 years

To all whom it may concern:

Be it known that I, Augustin Mlcoch, a citizen of Czechoslovakia, residing at Hulin, Czechoslovakia, have invented a new, original, and ornamental Design for Electrically Lighted Shoe, of which the following is a specification, reference being had to the accompanying drawing, forming part thereof, in which is shown a perspective view of a shoe embodying the design.

The essential feature of my design for a dancing shoe resides in the light transmitting ornamentation substantially as shown placed on the instep at the throat of the shoe.

I claim:

The ornamental design for electrically lighted shoe substantially as shown and described.

AUGUSTIN MLCOCH.
